UNITED STATES PATENT OFFICE.

ADOLPH WUNDER, OF NEW HAVEN, CONNECTICUT, ASSIGNOR TO SARGENT & CO., OF SAME PLACE.

DESIGN FOR SASH-LIFT.

Specification forming part of Design No. 5,347, dated October 31, 1871.

To all whom it may concern:

Be it known that I, ADOLPH WUNDER, of the city and county of New Haven and State of Connecticut, have invented a new and original Design for Sash-Lift; and I do hereby declare the following, when taken in connection with the accompanying drawing and the letters of reference marked thereon, to be a full, clear, and exact description, and which said drawing constitutes part of this specification and represents a front view.

This invention relates to a design for the article of manufacture known to the trade as "sash-lifts," that is, a device to be attached to the bottom rail of the lower sash, to serve as a handle by which to raise or lower the window-sash; and it consists in the peculiar configuration of the plate, as shown, and as more fully hereinafter described.

The outer sides of the plate are straight and at right angles to each other; but the corners

or angles are recessed and filled by a segment of a circle in the said recess, the opening or recess which forms the lift having parallel sides with curved ends, as fully shown in the accompanying illustration. Around the outer edge of the plate I form a plain raised edge, and a similar edge around the recess, thus giving to the surface of the plate the appearance of a sunken panel. The panel itself may be matted or otherwise finished, and ornamented by tracing or not, to suit the market. The edges and ornamentation (if any) are flush, so as to be polished or smoothed off together.

I claim—

The design for sash-lift, substantially as described and shown in the accompanying illustration.

ADOLPH WUNDER.
